UNITED STATES PATENT OFFICE

WILLIAM A. HINES, OF WICHITA, KANSAS, ASSIGNOR, BY MESNE ASSIGNMENTS, TO THE STANDARD TRAFFIC MARKER COMPANY, OF WICHITA, KANSAS, A CORPORATION OF KANSAS

STOP SIGN

Application filed August 14, 1926. Serial No. 129,113.

This invention relates to the general class of signals, but particularly to stop-sign signals, that is to signals which will indicate to drivers of vehicles that a stop or retardation of speed must be made at a road or street intersection.

Stop lines are ordinarily indicated by a painted line on the pavement of the street. Traffic soon obliterates this line so it becomes necessary to frequently repaint it.

My invention consists of a flexible sign or panel indicating caution or that a stop should be made at the intersection of the street or road. The sign consists of a base 15 adapted to be embedded in the ground, the base carrying a panel which has an inherent flexibility of such nature that it will tend to assume an up-right position whenever bending pressure is relieved and in order to reduce liability of breakage of the panel due to bending I prefer to provide bending shoulders adjacent to each face of the panel, the curve of each shoulder being preferably generated on an arc symmetrical with the curvature of the panel where it joins the base. The base and panel are preferably formed 20 integral and I prefer to place indicia on at least one face of the panel, the word "Stop" being an appropriate legend. The letters 25 of the legend are preferably counter-sunk or impressed below the surface of the panel, this protects the legend when the wheels of the vehicle run over the signal and it further has the advantage that the letters can be 30 easily repainted should occasion demand.

The invention will be better understood by reference to the following description in connection with the accompanying drawings in which:

40 The figure is a perspective view of a stop sign constructed in accordance with my invention the material in which the signal is embedded being shown in section.

The grade line of the street is indicated 45 at 1. There is a groove 2 in the street which

receives the base 3 of the sign. The base is preferably rectangular and it carries an up-standing panel 4 slightly tapered in cross-section with a bead 5 at its upper edge, the thickness of which is substantially equal to 50 the thickness of the portion 6 of the panel which is carried by the base. The sign is curved at the juncture of the base with the panel 4 as indicated at 7 and 8 conforming in curvature of the bend in shoulders 9 and 55 10 so that when the sign is bent over there will be no tendency to break or crack. On the side-wall of the portions 11 of the groove 2 are bending shoulders 12 and 13 making the portion 11 flared so that when the sign is 60 bent over due to pressure there will be no abrupt bend which would tend to crack it. The indicia indicated by the word "Stop" may be varied but in each instant I prefer to have the letters 14 sunk below the surface 65 of the sign so that in the event that a vehicle wheel passes over the panel the letters will not be marred. As heretofore pointed out the sinking of the letters has the added advantage that they may be easily repainted, since 70 the edges of the sunken letters act as guides for the brush. The sign may be made of a single piece as a new article of manufacture of any appropriate material which has an inherent flexibility and an inherent tendency 75 to spring back into shape, but I prefer to use rubber or rubber and fabric.

From the foregoing it will be seen that the sign can be easily embedded in the road-bed, but can be of such length and of such 80 height that any motor vehicle can straddle it without bending it over, but should it be bent over it will immediately spring back into the position shown in the drawing. Since it stands above the surface of the ground it will 85 be visible from a considerable distance and should the vehicle strike it no injury will result to either the sign or the vehicle.

What I claim and desire to secure by Letters-Patent is:—

1. As an article of manufacture, a stop sign comprising a substantially rectangular rubber panel having longitudinal flanges along its lower edge and indicia on the major portion of the panel.
2. As an article of manufacture, a stop sign comprising a substantially rectangular rubber panel having a longitudinal integral enlargement along its lower edge so that the lower edge of the panel is enlarged on both sides of the panel.

In testimony whereof I affix my signature.
WILLIAM A. HINES.
